UNITED STATES PATENT OFFICE.

CARL J. SCHULTE, OF CLEVELAND, OHIO, ASSIGNOR TO THE NATIONAL MALLEABLE CASTINGS COMPANY, OF CLEVELAND, OHIO, A CORPORATION OF OHIO.

RADIAL-DRAFT GEAR.

1,055,667.

Specification of Letters Patent. Patented Mar. 11, 1913.

Application filed February 8, 1911. Serial No. 606,803.

To all whom it may concern:

Be it known that I, CARL J. SCHULTE, a citizen of the United States, and a resident of Cleveland, in the county of Cuyahoga and State of Ohio, have invented a new and useful Improvement in Radial-Draft Gears, of which the following is a full, clear, and exact description, reference being had to the accompanying drawings, forming part of 10 this specification, in which—

Figure 1 is a partial plan view of my improved radial draft gear partly in section. Fig. 2 is a sectional side elevation of the same; and Fig. 3 is a diagrammatic plan view illustrating the principles of the invention.

My invention relates to an improvement in radial draft gears for railway cars in which the draft member is mounted on the 20 car-frame so as to swing in a horizontal plane and to adapt itself to the motion of the cars as they travel around the curves of the track, and in which the coupler is guided to the center of the track by means of a connection with the car-truck.

My improvement consists in a construction in which the guiding connections are mounted on the draft member and which are actuated by the movements of the car-truck, 30 and in the relation of the various parts of the draft gear which I shall hereinafter describe.

Referring now to Figs. 1 and 2, 2 represents the car coupler, whose shank 3 is provided with a long rearward extension 3', which may be made in one piece with the main portion of the shank, but is preferably a separate piece connected with the shank proper by a socket 4, having opposite lateral 40 recesses in which connecting plates 5 are fixed, preferably by bolts 6, which pass through the plates and through the socket and contained coupler shank. These plates extend upwardly and serve to give a floating 45 connection between the coupler shank and the buffer mechanism.

The extension 3' is curved upwardly at its rear end and is connected by a yoke or other suitable device 7 with a draft rigging 8, set 50 between the sills of the car. A tail bolt may, of course, be substituted for the yoke 7, and any suitable form of draft rigging, whether frictional or otherwise, may be employed.

The coupler shank extension is shown as 55 having a vertical pivot pin connecting it to

the yoke 7, so that when the car passes around curves the coupler and its shank may swing radially on the axis of the pin 9.

The buffer 10 is of the split shank type arranged above and to be swung radially 60 by the draft member and coupler. The buffer is provided at its rear end with springs 11 and 12, of which the inner coil 12 is considerably the longer of the two and is always under compression to keep the buffer 65 constantly pushed forward to the limit of its movement and insure a tight contact between the opposing car platforms. The outer and heavier spring comes into action after the buffer has been moved rearwardly 70 a predetermined amount. These springs are inclosed within a casing comprising two telescoping parts 13 and 14. The inner telescoping part 14 has a rearward extension with a forked guide portion 15, which fits over a 75 radial guide segment 16, secured to the car frame.

The divided shank 10' of the platform buffer incloses and is supported by the usual radial segment 17, which is firmly secured 80 to the center sills and upon which it slides in its radial movement.

The forward inclosing portion 13 of the telescoping casing is formed at its forward end with a reduced size filler portion 13^a, 85 which fits between and forms a spacer for the rear end portion of the buffer shank. This portion 13^a is preferably formed with tubular spacing bosses 18, through which extend securing bolts 19, which firmly clamp 90 the buffer shank and the telescoping casing together, the rear ends of the shank abutting against the forward end of this casing proper. The lower leg of the divided platform buffer is provided 95 with a depending hollow portion 20, to which is bolted a carry-iron 21, surrounding and supporting the shank 3 of the coupler. The coupler is thus supported by and moved with the buffer in the radial 100 movement. In this form the guiding connection arm 22 with its centering springs and attachments is not secured to the truck frame but to the radially swinging draft member. This guiding arm 22 is pivoted by 105 a vertical pin connection 23 to the front end of a stem 24, having an adjustable stop 25, between which and a portion of the bracket 26, secured to the draft member, are interposed the centering springs 27 and 28. The 110

arm 22 is widened in its rear portion, as shown in Fig. 1, and its side rear portions 29 are provided with sockets to receive the fulcrum portions 30 at the sides of the bracket. The arm 22 is inclined or curved forwardly and downwardly and terminates in a ball portion 31, which fits within a corresponding socket 32. This socket member 32 is preferably made in one piece with an open lower side, its lower portion having inwardly projecting lugs or guide flanges which slide under outwardly projecting ribs, forming longitudinal guide portions of a casting or bracket 35, secured to and projecting forwardly from the central portion of the truck frame.

In assembling the parts, the single-piece socket is slipped down vertically over the ball portion of the arm, and after being so arranged is slid rearwardly between the guides of the bracket casting on the truck frame. When this single-piece socket is in engagement with the guides upon the bracket and the guiding connections are attached to the draft member, it is impossible to disengage the ball-and-socket connection, since the socket can only be released by an upward movement, which is prevented on account of its engagement with the longitudinal guides on the truck frame bracket.

The guiding arm 22 is normally held parallel with the draft member and can only be displaced from alignment therewith by compression of the centering springs 27 and 28. Any movement of the arm 22 relative to the draft member causes a fulcruming action which will compress the springs, which, in turn, tend to return it to its normal aligned position. The sliding engagement of the socket member 32 with the truck frame guide allows the radially swinging draft arm with the attached parts to have longitudinal movement relative to the truck frame both in buffing and in draft; while the truck frame, as the truck turns in passing around curves, will guide the radially swinging draft member laterally and bring the coupler to the center of the track by its engagement with the centering arm 22.

50 The yielding centering spring mechanism is used with the guiding connections, in order that a certain amount of independent or abnormal side play may be allowed for the draft member without bringing undue stress upon the parts, thus providing for the conditions which occur when a car equipped with such radial draft gear is coupled to an ordinary car. In this case the center of the socket connection between the arm 22 and the socket 32 is the actuating point hereinabove referred to. The position of this actuating point is determined in accordance with the diagram shown in Fig.

55 3. In this figure the point A is termed the coupling point, being the point where the

longitudinal center line of the coupler intersects the inner face of the outer arm of its knuckle, that is, the face which contacts with the corresponding face of an interlocked knuckle, in pulling, and B is the 70 pivotal point of the draft member. By passing a vertical plane through the pivotal point of the draft gear to the coupling point, as indicated at a, a, and another vertical plane bisecting the truck at right angles thereto, as indicated at b, b, the intersection of these planes will give a vertical line in which the actuating point in the socket connection between the guide arm 22 and the truck should lie. When this actuating point 80 is thus located (except under abnormal deflection as in the case of coupling with an old style car), the coupler will be accurately guided to the center of the track whether on a straight or curved portion of the track. 85 Of course the three points may also be located by fixing any two of them and similarly locating the third by the system above described. That is, the actuating point C may be fixed, the coupling point fixed and the pivot of the draft gear then determined by the use of the planes. Similarly the pivotal point and the actuating point may be fixed and the coupling point then determined. It may not be possible in certain cases to make 95 the pivotal point of the draft gear at the exact point placed by this system, but it should be placed as near this point as possible to give the desired results.

The advantages of my invention result 100 from the application of the broad principle set forth in the patent of H. T. Krakau No. 947,244, dated January 25, 1910 to a case where the intersection of the planes determines, not the point at which the guiding connections shall engage and actuate the draft member, but the point at which the guiding connections shall engage and be actuated by the truck, or at which the draft member and truck shall engage each other directly. 110

115 My invention provides for proper action of the draft gear and coupling under all conditions, while the actuating engagement is not between the guiding connections and the draft member.

I claim:-

1. In a radial draft gear, a laterally 120 swinging draft member pivotally mounted on a car, a guide-arm flexibly mounted on the draft member, the said guide-arm having a bearing on an inflexible portion of the truck, by which movement is transmitted 125 from the truck to the draft member when the car is passing around a curve.

2. A radially swinging draft member pivotally mounted on a car in the longitudinal center line thereof and in advance of the 130

truck center, said member being adapted to swing horizontally, and guiding connections flexibly mounted on the draft member and having a bearing on an inflexible portion of the truck by which movement is transmitted from the truck to the draft member when the car is passing around a curve, said bearing always lying substantially at the intersection of a vertical plane bisecting the truck 10 at right angles and a vertical plane passing through the pivotal point of the draft gear and the coupling point, except when the draft member is abnormally deflected.

3. In a radial draft gear, a laterally swinging draft member, and a guiding arm secured to said member and having a yielding connection therewith, the forward end

of said arm having a swinging and longitudinally sliding engagement with a portion of the truck frame, the point of connection of the said arm and the truck frame being forward of the forward axle of the truck, substantially as described. 20

4. In a radial draft gear, a guiding connection having a ball-and-socket joint with 25 a one-piece socket held in place by longitudinal guideways, substantially as described.

In testimony whereof, I have hereunto set my hand.

CARL J. SCHULTZ.
